UNITED STATES PATENT OFFICE.

CHESTER T. ALLCUTT, OF PITTSBURGH, PENNSYLVANIA, ASSIGNOR TO WESTINGHOUSE ELECTRIC & MANUFACTURING COMPANY, A CORPORATION OF PENNSYLVANIA.

HIGH-FREQUENCY-CORONA-DISCHARGE FURNACE.

Application filed October 27, 1923. Serial No. 671,1.

To all whom it may concern:

Be it known that I, CHESTER T. ALLCUTT, a citizen of the United States, and a resident of Pittsburgh, in the county of Allegheny 5 and State of Pennsylvania, have invented a new and useful Improvement in High-Frequency - Corona - Discharge Furnaces, of which the following is a specification.

My invention relates to electric heating 10 and it has for its object to provide a method of and means for heating by a high-frequency corona discharge.

In practicing my invention, I provide a source of high-frequency current supply of 15 sufficiently high voltage to produce a corona discharge between a pair of co-operating electrodes and adjacent to a mass of material to be heated thereby.

In the single sheet of drawings, 20 Figure 1 is a schematic view of a heating system embodying my invention, the furnace part thereof being shown in section,

Fig. 2 is a schematic view of a modified form of heating system embodying my in- 25 vention,

Fig. 3 is a view in vertical section of an electric furnace for use with my system, and Fig. 4 is a top plan view thereof.

Referring more particularly to Fig. 1 of 30 the drawing, a container 11 for a mass of material 12 to be heated, may be built up of any suitable refractory material that will resist a relatively high temperature. The container is preferably composed of con- 35 ducting refractory material, such as graphite, although a non-conducting material may be employed, particularly if the charge 12 is of conducting material. A circular electrode 13 surrounds the container 11 and is 40 spaced therefrom a suitable distance. The inner peripheral surface of the electrode 13 may be provided with a plurality of in- wardly projecting points 14.

The electrode 13, which is of a suitable 45 electric-conducting material, is connected to one terminal of the secondary winding of a transformer 15, the other terminal of which is connected to the crucible 11 and also to the charge 12 placed therein. The trans- 50 former 15 is intended to schematically represent a source of sustained electric current of high voltage and of high frequency, and I have included a condenser 16 in parallel circuit relation to the secondary winding of

the transformer and the furnace constituted 55 by the container 11 and the electrode 13 to neutralize the inductive reactance of the transformer 15.

If the source of supply 15 is suitably en- 60 ergized, a relatively high-frequency and high-voltage electric current is delivered to the electrodes constituted by the member 13 and the member 11 and if the voltage is sufficiently high, the air becomes ionized and a corona discharge is produced at the points 65 14. This discharge is of relatively high temperature and the heat therefrom will be radiated or otherwise transmitted through the crucible 11 to the mass 12 of material located thereon, which is to be heated. 70

It is desirable, in heating systems of this kind, to stabilize the discharge as otherwise the electrical discharge may take the form of a spark discharge between a relatively few points on the surface of the electrodes 75 and thereby cause local heating.

In Fig. 2 of the drawing, I have illus- 80 trated a construction comprising a container 11 with a mass of material 12 located therein. An electrode 17 of metal may be located closely adjacent to and around the outer sur- 85 face of a crucible 18 of a dielectric material, such as quartz and spaced from the outer surface of the crucible 11.

The quartz crucible acts as a condenser in 90 series with the ionized air gap between it and the container 11. The action of the condenser is such as to prevent a spark discharge being established over any individual portion of the electrode or of the mate- 95 rial-containing crucible. The prevention of a spark discharge is desirable, since such a discharge would occur between a few points only on the opposing surfaces of the elec- 95 trodes and would cause localized heating.

In Figs. 3 and 4, I have illustrated a relatively simple electric furnace structure that 100 may be employed in the system embodying my invention. The inner crucible and electrode 11 containing the mass 12 of material to be heated is made relatively small in lateral cross-section and may be made relatively deep to receive the desired amount of material at one time. An outer electrode 19 is formed in the shape of a crucible and is 105 of much larger area of cross-section than the container 11. A mass 21 of porous refractory electric-insulating material, such as

coarse sand or gravel or lumps of magnesia, may be employed to fill the space between the electrodes to reduce the heat losses that would be caused by convection currents of air.

If the outer dimensions of the container 11 are made relatively very small as compared to the dimensions of the outer electrode 19, the corona discharge will be established upon the surface of the inner electrode container 11 when the terminals of a suitable source of supply of high-frequency and high-voltage electric energy is connected to the respective electrodes. This condition exists for the reason that the electric stress at any point on the surface of the inner electrode container 11 is very much greater than that on a corresponding and co-operating surface portion of the outer electrode 19. Hence, the corona discharge will be established on substantially the outer surface of the container 11 and the heat generated thereby will be transmitted through the walls of the container to the mass of material to be heated that is located therein.

That portion of the air path lying between the electrode 19 and the outer limits of the corona discharge formed on the outer surface of the crucible 11 is substantially unionized and hence acts as a relatively perfect condenser dielectric for stabilizing the corona discharge.

Where I have referred to a high frequency alternating current, I desire it to be understood that reference is made to frequencies not less than those usually employed in radiotelegraphy and radiotelephony and such higher frequencies as may be commercially produced for such applications. An alternating current of sustained high frequency is particularly applicable for my purpose, as the discharges from a series of high frequency wave trains, such as produced by an oscillatory spark discharge will not effect the desired heating.

Various modications and changes may be made without departing from the spirit and scope of the invention, I desire, therefore, that only such limitations shall be placed thereon as are imposed by the prior art or are set forth in the appended claims.

I claim as my invention:

1. In a heating system, in combination, a crucible for containing a charge to be heated, and means for producing a corona discharge adjacent to said crucible to heat the same.

2. In a heating system, in combination, a crucible for containing a charge to be heated, and means for producing a high-frequency corona discharge adjacent to said crucible to heat the same.

3. An electric furnace comprising a

charge to be heated and means for producing a corona discharge adjacent thereto to heat the same.

4. An electric furnace comprising a charge to be heated and means for producing a high-frequency corona discharge adjacent thereto to heat the same.

5. In a heating system, in combination, a crucible for containing a charge to be heated, an electrode adjacent to said crucible and spaced therefrom, and means electrically connected to said crucible and said electrode for producing a corona discharge adjacent to said crucible for heating the same.

6. In a heating system, in combination, a material container of relatively small external dimensions; an electrode, of relatively large dimensions, surrounding said container, and means for producing an alternating electric field of high potential between said container and said electrode.

7. The method of heating material which comprises the production of a corona discharge adjacent to a crucible containing said material.

8. The method of heating material which comprises placing a crucible containing the same in a high-frequency electric field of sufficiently high voltage to produce a corona discharge adjacent to said crucible.

9. In a heating system, in combination, a crucible for containing a charge to be heated, means for producing a corona discharge from said crucible to heat the same and means for stabilizing said corona discharge.

10. In a heating system, in combination, a crucible for containing a charge to be heated, means for producing a corona discharge from said crucible to heat the same and means for insuring a substantially uniform distribution of heating effect over said crucible.

11. In a heating system, in combination, a crucible for containing a charge to be heated, means for producing a corona discharge from said crucible to heat the same and means comprising a condenser for insuring a substantially uniform distribution of current over said crucible.

12. In a heating system, in combination, a crucible for containing a charge to be heated, an electrode adjacent to said crucible and spaced therefrom, means electrically connected to said crucible and said electrode for producing a corona discharge adjacent to said crucible for heating the same, and means located between said crucible and electrode for stabilizing said corona discharge.

In testimony whereof, I have hereunto subscribed my name this 22nd day of October, 1923.

CHESTER T. ALLCUTT,
